SEWING MACHINE

Clarence C. Smith, Chicago, Ill., assignor to
Union Special Machine Company, Chicago, Ill.,
a corporation of Illinois

Application September 7, 1946, Serial No. 695,487

6 Claims. (Cl. 112—215)

1

The present invention relates to sewing machines and more particularly, to the feed mechanism for such machines. It is an object of the invention to provide means for regulating the extent of feeding motion of the feed mechanism of a sewing machine.

A further object of the invention is to provide a simple, easily operated and accurate feed regulating means for sewing machines.

A further object of the present invention is to provide a feed regulating means which is substantially vibrationless in operation and thus is particularly adapted for use in high-speed sewing machines.

It is a further object of the present invention to provide feed regulating means of the character described above which is exceedingly durable and which includes provision for simple compensation of such wear as may occur.

Other and further objects of the present invention will in part be obvious and will in part become apparent upon a consideration of the following description of a preferred but not necessarily the only embodiment of the invention taken in connection with the drawings accompanying and forming a part of the present specification.

In the drawings:

Fig. 1 is a vertical section of a sewing machine to which the present invention may be adapted;

Fig. 2 is a horizontal section along the line II—II in Fig. 1;

Fig. 3 is an end elevational view partly in section of the machine as viewed from the left in Fig. 1;

Fig. 4 is an end elevational view, from the right in Fig. 1, with portions broken away to illustrate interior parts of the machine;

Fig. 5 is a vertical sectional view taken on the line V—V in Fig. 2;

Fig. 6 is an enlarged, detailed view in horizontal section taken in a plane slightly below the plane of Fig. 2;

Fig. 7 is a vertical sectional view along the line VII—VII in Fig. 6; and

Fig. 8 is an enlarged, detailed sectional view of certain parts of the machine.

Referring now to the drawings, the present invention has been illustrated as embodied in a lockstitch sewing machine of known type. It will be understood, however, that the present invention is adaptable to substantially any form of sewing machine in which a feed-dog is used. In Fig. 1 the machine shown includes a hollow base having a removable bottom wall 10 and sealing gasket 11 and a top wall or cloth plate 12. In

2

Fig. 2 it will be observed that the base is provided with front and rear walls 14 and 16. The base also includes a right end wall 18 and a left end wall 19, these walls being identified as right and left merely for the purpose of orientation. The hollow base just described contains certain elements of the sewing mechanism and as shown in Fig. 1, contains upper and lower oil-sumps 20 and 21, respectively.

10 The machine includes a hollow standard 22 which communicates at its lower end with the hollow base just described and which may have integrally formed therewith a hollow arm 24 terminating in a head 26.

15 The main operating shaft of the machine is shown at 28 in Fig. 1. This shaft extends through the arm 24 and carries at its outer end a combined hand and belt wheel 30 by which the machine may be operated either manually or under power. The head 26 has mounted therein for vertical reciprocation a needle bar 32 carried in bushings 33 and 34 within the head 26. At its lower end the needle bar may be fitted with a needle 36. The shaft 28 has secured thereto within the head 26 a crank head 38 which is connected through a link 40 to the needle bar 32 to impart thereto one complete reciprocation upon each revolution of the main driving shaft 28.

20 The shaft 28 has fixed thereto within the hollow standard 22 a gear 42 meshing with an idler gear 44 carried upon a suitable shaft 45 rotatably mounted in bushings provided in the hollow standard 22. The idler gear 44 meshes with a gear 46 fixed to a shaft 48 extending longitudinally of the hollow base. In the particular machine chosen for illustration herein the gears 46 and 42 are of the same diameter whereby the shaft 48 is driven at the same angular speed as the shaft 28. The shaft 48 is carried in suitable

25 bearings 49, 50 and 51 mounted in suitable web or lug formations in the base casting. The shaft 48 has fixed thereto a gear 52 which meshes with a gear 54 fixed to a hook shaft indicated generally at 56. At its lefthand end, as shown in Fig. 1, the hook shaft 56 carries a rotary hook 58. The hook 58 has been omitted from Fig. 2. It will be

30 understood that the loop-taking mechanism of the machine may be of any suitable form, the rotary hook shown in the present embodiment being merely an illustration. In the present embodiment the ratio between gears 52 and 54 is such that the rotary hook is driven at twice the angular speed of the shaft 48.

35 Referring next to Fig. 3, the feed mechanism includes a feed-dog 60 the teeth

40 of which are shown at 62. The feed-dog 60 is carried in a frame 64 which is secured to the base 10. The frame 64 includes a top plate 66 and a bottom plate 68. The feed-dog 60 is secured to the top plate 66. The frame 64 is secured to the base 10 by a

45

of which work through suitable slots (not shown) in a throat plate 62 to cooperate with the usual presser foot 64 in feeding the work through the machine. The feed-dog 60 is adjustably secured as by a screw and slot arrangement 66, 67 to a carrier or feed bar 68 and may be vertically adjusted with respect thereto by a screw 69. The carrier 68 has a cylindrical extension 70 passing through a clearance opening 72 in a longitudinal offset portion 74 of the left end wall 19 of the base. The carrier extension 70 is secured in a socket member 76 as by set screws 78 (see Fig. 2). The socket member 76 has a transverse boss 80 which is freely rotatable upon a pin 82 extending between a pair of arms 84 of a feed-rocker 86. The rocker 86 is pivoted upon a longitudinally extending shaft 88 (see Fig. 3) which extends between bushings 90 and 91, respectively, in the end wall 19 and a laterally offset portion 92 of the rear wall 16. Preferably the bushings and the shaft 88 are held against movement as by set screws 93.

Referring now to Fig. 5, the feed-rocker 86 also includes a pair of arms 94 rotatably carrying a pin 96 to which a hub 98 is secured as by a set screw 97.

Referring again to Fig. 2, it will be observed that the hub 98 carries at right angles thereto a tubular member 100 which receives a plunger 102 integral with part of an eccentric strap 104 encompassing an eccentric or crank 106 (see Fig. 8) formed on the shaft 48. The tubular member 100 and plunger 102 comprise a telescopic pitman which serves to connect the feed-rocker 86 with the crank 106. Inasmuch as the hub 98 and pin 96 are free to pivot on the feed-rocker, it will be apparent that the mechanism, as so far described, will not be effective to produce rocking of the feed-rocker 86 because the pitman 100, 102 will merely telescope while freely in-swinging about the pin 96. In the present invention the motion of the telescopic pitman 100, 102 is modified by an exceedingly simple mechanical arrangement which may be readily adjusted to vary the extent of movement of the feed-rocker from substantially zero to an extent adequate for the formation of the longest stitch which it may be desired to form on any particular machine. It is this latter mechanism to which the present invention is particularly directed.

The mechanism for regulating the movement of the feed-rocker 86 includes a longitudinally extending regulating shaft 108 journalled in bearings located respectively in a wall portion 110 at the right end of the base and a lug 112 formed on the rear wall of the base. At its right end the shaft 108 carries an arm 114 which may be adjustably secured to shaft 108 as by a set screw 116 (see Fig. 4). A torsion spring 118 is shown in Figs. 2 and 4 and is so arranged as to bear against a lateral extension 120 of the arm 114 and to tend to rotate the arm 114 and shaft 108 in a counterclockwise direction as viewed in Fig. 4.

A longitudinally adjustable rod 122 extends generally transversely of the right end of the base. One end of rod 122 abuts against the arm 114. At its other end the rod 122 is provided with a threaded portion 124 received in a threaded bore 126 in the base casting. A suitably graduated regulating knob 128 is also fixed for rotation with the rod 122 whereby the rod 122 may be projected or retracted with respect to the arm 114. Thus, adjustment of the rod 122 by manual turning of the knob 128 will determine the an-

gular position of the regulating shaft 108 under influence of the torsion spring 118.

Referring to Fig. 2 and Fig. 6, the shaft 108 has fixed at its forward end a generally cylindrical collar 130. The collar 130 may be secured to the shaft 108 by set screws 132 or the like. The collar 130 has formed in the lefthand face thereof, as viewed in Fig. 2 or Fig. 6, a diametrically disposed slot 134 which serves as a slideway for a block 136 (see Fig. 7). The block 136 is freely rotatable upon a reduced portion 138 of a stud 140 secured to the tubular member 100 of the telescopic pitman. It will be apparent that rotation of the regulating shaft 108, as by turning the knob 128, will result in changing the angular position of the slot or slideway 134 relative to the longitudinal axis of the telescopic pitman 100, 102. If the regulating shaft is adjusted to such position that the slot 134 is substantially normal to the axis of the pitman when the latter is in its intermediate position, there will be substantially no rocking movement imparted to the feed-rocker 86 when the machine is operated. In such adjusted position the block 136 will move up and down in the slot 134 and thus in a path which is tangent to the arc in which the block 136 would move if unconfined. Since the length of the arc is very short compared to the radius thereof, the confining of the block 136 to a tangential path will cause only a very slight rocking of the feed-rocker 86. This very slight movement may be ignored for practical purposes and the feed-rocker 86 may be considered to be substantially stationary. However, if the angular position of the slot 134 is changed even a very small amount, a relatively great modification of pitman movement will occur. Thus the knob 128 may be rotated to vary the angular position of slot 134 and thus to vary the amplitude and relative direction of rocking of the feed-rocker 86.

In the machine chosen for illustration herein the feed-rocker motion may be so varied by adjustment of the slot 134 from normal to approximately twenty-one degrees on either side of normal as to produce effective feed-dog motion of from substantially zero to approximately five thirty seconds of an inch in either direction. While it will be recognized that such a range of adjustment is adequate for the great majority of sewing machines, such range may be very much increased if so desired by tilting the slot 134 through a greater range. It has been found that the slot 134 may be tilted in either direction as much as thirty degrees without causing rough or irregular movement or undue wear.

It will be understood that adjustment of the slot 134 to an angular position other than generally normal to the longitudinal axis of the telescopic pitman 100, 102 will result in confinement of the block 136 to a path not tangential to its normal arc of movement and that the effect will be to draw the tubular telescopic member 100 forwardly or project it rearwardly as viewed in Figs. 2 and 6, dependent upon the direction in which the slot 134 has been tilted. Within the limits necessary to secure adequate feed-dog regulation the modification of pitman movement is effected without establishing angular relationships between the parts which might result in undue strain or rapid wear. The slotted collar 130 may be made of hardened metal and in such event may be expected to have a life fully comparable to most of the other parts of the machine. Preferably the block 136 is formed as a

square as viewed in Fig. 7 whereby in the event looseness should eventually develop as a result of wear of the faces in contact with the sides of slot 134, the block may be removed and turned through ninety degrees to present new bearing surfaces.

If so desired, the tubular member 100 may be provided with a lug 142 having a flat bearing surface on its left-hand end as viewed in Fig. 6. A stud 144 is seated in a suitable recess 145 in the left end wall 19 in an opposed position with relation to the lug 142. The stud 144 has an enlarged head 146 presenting a flat bearing surface for cooperation with the bearing surface of the lug 142. The stud 144 may be held in adjusted position by a set screw 148 and normally will be so adjusted as to abut the lug 142 to prevent sidewise movement of the telescopic pitman 100, 102 during operation of the machine.

The mechanism described above provides for regulation of the extent of the horizontal components of feeding motion of the feed-dog 60 and it is believed that the operation and advantages thereof have been fully disclosed. In the machine chosen for illustration of the present embodiment of the invention the feed-dog 60 has a four-motion feed the vertical components of which are produced by the mechanism now to be described.

The feed-dog carrier 68 is provided with a downwardly projecting extension 150 freely pivoted at its lower end to the lower end of a link 152 (see Figs. 3 and 8). The link 152 is freely pivoted at its upper end upon an eccentric or crank 154 formed upon the left-hand end of the shaft 48. Rotation of the shaft 48 therefore will be effective to swing the carrier 68 about the center of the pin 82 in the feed-rocker 86 and thus to impart vertical movement to the feed-dog 60.

While an illustrative form of the invention has been disclosed in considerable detail, it will be understood that various changes may be made in the construction and arrangement of the several parts without departing from the general principles and scope of the invention as defined in the appended claims.

I claim:

1. In a sewing machine a frame, a feed-dog, an operating shaft, a feed-rocker for imparting movement to said feed-dog, an eccentric on said operating shaft, a pitman connecting said eccentric with said feed-rocker, said pitman including telescoping members having a free-sliding connection one with the other and one of said telescoping members being freely pivoted to said feed-rocker, a slotted guiding member, a regulating shaft rotatably mounted in said frame and having said slotted guiding member secured thereto in a position wherein the longitudinal axis of the slot in said slotted guiding member extends transversely of the longitudinal axis of said regulating shaft, a block freely pivoted on said one of said telescoping members and having at least two parallel sides extending into the slot in said slotted guiding member for sliding motion longitudinally of said slot as an incident to swinging of said telescopic pitman to impart endwise motion to said one member of said telescopic pitman and thereby to impart an oscillating motion to said feed-rocker to variable extents dependent upon the angular relationship between the longitudinal axis of the slot in said slotted guiding member and the longitudinal axis of said telescopic pitman, a lever secured to said

5 regulating shaft, and means including an adjustable abutment carried by said frame for holding said lever in fixed but adjustable positions to regulate the extent of oscillating motion imparted to said feed-rocker.

2. In a sewing machine a frame, a feed-dog, an operating shaft, a feed-rocker for imparting movement to said feed-dog, an eccentric on said operating shaft, a pitman connecting said eccentric with said feed-rocker, said pitman including telescoping members having a free-sliding connection one with the other and one of said telescoping members being freely pivoted to said feed-rocker, a slotted guiding member, a regulating shaft rotatably mounted in said frame and having said slotted guiding member secured thereto in a position wherein the longitudinal axis of the slot in said slotted guiding member extends transversely of the longitudinal axis of said regulating shaft, a block freely pivoted on said one of said telescoping members and having at least two parallel sides extending into the slot in said slotted guiding member for sliding motion longitudinally of said slot as an incident to swinging of said telescopic pitman to impart endwise motion to said one member of said telescopic pitman and thereby to impart an oscillating motion to said feed-rocker to variable extents dependent upon the angular relationship between the longitudinal axis of the slot in said slotted guiding member and the longitudinal axis of said telescopic pitman, a lever secured to said regulating shaft, and means comprising an adjustable abutment carried by said frame and spring means constantly urging said lever into engagement with said abutment for holding said lever in fixed but adjustable positions to regulate the extent of oscillating motion imparted to said feed-rocker.

3. In a sewing machine a frame, a feed-dog, an operating shaft, a feed-rocker for imparting movement to said feed-dog, an eccentric on said operating shaft, a pitman including telescoping members having a free-sliding connection one with the other and one of said telescoping members being freely pivoted to said feed-rocker, a slotted guiding member, a regulating shaft rotatably mounted in said frame and having said slotted guiding member secured thereto in a position wherein the longitudinal axis of the slot in said slotted guiding member extends transversely of the longitudinal axis of said regulating shaft, a block freely pivoted on said one of said telescoping members and having at least two parallel sides extending into the slot in said slotted guiding member for sliding motion longitudinally of said slot as an incident to swinging of said telescopic pitman whereby to impart endwise motion to said one member of said telescopic pitman and thereby to impart an oscillating motion to said feed-rocker to variable extents dependent upon the angular relationship between the longitudinal axis of the slot in said slotted guiding member and the longitudinal axis of said telescopic pitman, a lever secured to said regulating shaft, adjustable means engageable with said lever for swinging said lever and rotating said regulating shaft, spring means constantly urging said regulating shaft to rotate in one direction, and means accessible from the outside of said frame for moving said adjustable means to vary the position of the slot in said slotted guiding member to regulate the extent of oscillating motion imparted to said feed-rocker.

4. In a sewing machine a frame, a feed-dog, an

operating shaft, a feed-rocker for imparting movement to said feed-dog, an eccentric on said operating shaft, a pitman connecting said eccentric with said feed-rocker, said pitman including telescoping members having a free-sliding connection one with the other and one of said telescoping members being freely pivoted to said feed-rocker, a slotted guiding member, a regulating shaft rotatably mounted in said frame and having said slotted guiding member secured thereto in a position wherein the longitudinal axis of the slot in said slotted guiding member extends transversely of the longitudinal axis of said regulating shaft, a block freely pivoted on one of said telescoping members, said block having a plurality of pairs of opposed equally spaced parallel faces the spacing between the faces of each of said pairs being such that the faces in any pair may be arranged in sliding relationship respectively with opposed walls of the slot in said slotted guiding member, said block extending into the slot in said slotted guiding member for sliding motion longitudinally of said slot as an incident to swinging of said telescopic pitman whereby to impart endwise motion to the member of said telescopic pitman to which said rectangular block is freely pivoted and thereby to impart an oscillating motion to said feed-rocker to variable extents dependent upon the angular relationship between the longitudinal axis of the slot in said slotted guiding member and the longitudinal axis of said telescopic pitman, a lever secured to said regulating shaft, and means accessible from the outside of said frame for engaging and moving said lever to vary the position of the slot in said slotted guiding member to regulate the extent of oscillating motion imparted to said feed-rocker.

5. In a sewing machine a frame, a feed-dog, an operating shaft, a feed-rocker for imparting movement to said feed-dog, an eccentric on said operating shaft, a pitman connecting said eccentric with said feed-rocker, said pitman including telescoping members having a free-sliding con-

nexion one with the other and one of said telescoping members being freely pivoted to said feed-rocker, a follower projection extending laterally from said one telescoping member, a slotted guiding member adapted to receive said follower projection to impart oscillating motion to said feed-rocker, a bearing projection extending laterally from said one telescoping member in a direction opposite to said follower projection, and an abutment on said frame positioned to engage said bearing projection.

6. In a sewing machine a frame, a feed-dog, an operating shaft, a feed-rocker for imparting movement to said feed-dog, an eccentric on said operating shaft, a pitman connecting said eccentric with said feed-rocker, said pitman including telescoping members having a free-sliding connection one with the other and one of said telescoping members being freely pivoted to said feed-rocker, a follower projection extending laterally from said one telescoping member, a slotted guiding member adapted to receive said follower projection to impart oscillating motion to said feed-rocker, a bearing projection extending laterally from said one telescoping member in a direction opposite to said follower projection, an abutment on said frame having a bearing surface aligned with said bearing projection, and means for adjustably securing said abutment in position to cooperate with said bearing projection to guide said one telescoping member.

CLARENCE C. SMITH.
